UNITED STATES PATENT OFFICE.

GEORGE BULLOCK AND ARTHUR E. TEMPLEMAN, OF GRAND JUNCTION, COLORADO.

ELECTRIC IRON.

1,282,040.

Specification of Letters Patent. Patented Oct. 22, 1918.

Application filed March 28, 1918. Serial No. 225,208.

To all whom it may concern:

Be it known that we, GEORGE BULLOCK and ARTHUR E. TEMPLEMAN, citizens of the United States, residing at the city of Grand Junction, county of Mesa, and State of Colorado, have invented a new and useful Electric Iron, of which the following is a specification.

This invention relates to electric irons.

10 An object of the invention is to provide a device adapted to be connected with the handle structure of an electric iron for supporting the cord or wires to which the iron is connected in order to support the same 15 out of the way during operation of the iron, said device being provided with engaging means constituting a part of the device whereby the same will be supported in an upright position without the use of special 20 detachable connecting elements.

Another object of the invention is to provide a support of the character mentioned constructed so that a part thereof will engage directly with parts of the handle structure so that the support will be held in nearly an upright position firmly and with a sufficient degree of rigidity without the use of such expedients as binding screws, or other detachable clamping or connecting 30 elements.

Other objects will appear from the detailed description in which reference is made to the accompanying drawing, illustrating the preferred type of our invention where- 35 in—

Figure 1 is a side elevation of an electric iron having the device in connection therewith.

Fig. 2 is an enlarged perspective view of 40 the device detached from the electric iron.

Fig. 3 is a view looking toward the upper end of the device.

Figs. 4, 5 and 6 are sectional views on the lines 4—4, 5—5 and 6—6 respectively of 45 Fig. 2.

The electric iron shown is of a well known type in which the handle 1 is carried by a support 2 composed of a metallic plate bent to proper shape and secured to the iron by 50 the connections 3.

As usual the electric wires by which the electric current is conducted to the iron for heating the same are inclosed within a fabri-

cated cord 4 and are in connection with a plug 5 having detachable connection with 55 a socket 6 carried by the iron.

Our present invention consists of a support adapted to be connected with the handle structure without the use of any of the usual detachable connecting elements and arranged to support the wires or cord out of the way so that the iron may be operated without interference. The support is composed of any material appropriate for that purpose and in the form shown is composed 60 of sheet metal bent to provide a base portion 7 and an upright portion shaped to provide several functional elements and features for holding the support in connection with the iron and for engaging the cord inclosing the 70 electric wires. The base 7 is arranged to fit against the under side of the handle supporting plate 2 as shown in Fig. 1, and is provided with a bifurcated end which is effected by a notch 8 cut in the extremity 75 of the base 7 thus leaving two arms adapted to engage on opposite sides of one of the connecting members 3 by which the handle is held in connection with the iron.

The upright cord supporting portion of 80 the support is bent to annular shape in cross section and is formed with two projections 9 adapted to embrace the handle supporting plate 2 below the handle. Said projections are arranged so that they will effect firm 85 engagement with the handle supporting plate and thus hold the device in its upright position.

The upright portion above the projections 9 is preferably formed with a socket 10 for 90 receiving the end portion of the handle 1 and thus coöperating with the projections 9 to sustain the support. The socket 10 is formed by a proper conformation of the side edges of the sheet metal as will be 95 understood by reference to Fig. 2.

Above the socket the supporting element is bent to a nearly semi-tubular shape so that the cord of the electric iron will, to a great extent, be received between the side 100 edges of the sheet metal support.

At a proper altitude above the socket 10 a pair of projections are formed integral with the upright portion of the support including converging portions 11 and outwardly diverging portions 12, the latter

2
forming a guide by which the cord is guided when pressed between the projections into the clamping portion thereof. The upper end of the supporting member is also formed 5 with a pair of projections 13 which extend obliquely upwardly and which also have converging and diverging portions thereon so that they will efficiently perform their function. The purpose of making the projections 10 13 in oblique positions is to permit the cord to pass therefrom without a tendency to force the cord from within the clamp during the operation of the iron. From the foregoing it is apparent that our present invention 15 consists of a very convenient support capable of being quickly applied to and removed from an electric iron without any inconvenience attendant upon the use of separable fastening connections. The device is entirely 20 self-contained and in fact is in one integral structure and is therefore of greater convenience and utility than the usual devices which require separate fasteners for connecting them to the iron.

We do not restrict ourselves to the construction of the device of sheet metal, nor to any particular shape or design of the retaining devices, nor to any other unessential details or features of construction.

30 What we claim and desire to secure by Letters Patent, is:—

1. A device of the character described, comprising a supporting arm, a socket in connection with the supporting arm for engaging with the handle of an electric iron, and means in connection with the supporting arm for engaging with the handle connecting device.

2. In an electric iron having a handle, a support for the handle, and a device holding the handle support in connection with the iron; a supporting arm, means supported by the supporting arm for releasably engaging the handle, and means in connection 45 with the supporting arm for engaging the handle holding device, whereby said arm will be held in an upright position.

3. In an electric iron having a handle, a support for the handle, and a device holding the handle support in connection with the iron; a supporting arm, a socket in connection with the supporting arm for releasably engaging the handle of the iron, and means in connection with the supporting arm for 55 engaging the handle holding device, whereby said supporting arm will be held in an upright position by the coöperation of said socket and said means with the parts of the electric iron engaged thereby respectively.

60 4. In an electric iron having a handle, a support for the handle, and a device connecting the support with the iron; a supporting arm, a socket in connection with the supporting arm for releasably engaging the handle 65 of the iron, and a bifurcation in connection

with the supporting arm for engaging said device, whereby the supporting arm will be held in an upright position by the coöperation of said socket and said bifurcation with the parts engaged thereby respectively. 70

5. In an electric iron having a handle, a support for the handle, and a device connecting the support with the iron; a supporting arm, means in connection with the supporting arm for engaging said device, a 75 socket in connection with the supporting arm for engaging the handle, and a clamp device in connection with the supporting arm for engaging the handle support below the handle. 80

6. A device of the character described, comprising a supporting arm, a socket in connection with said supporting arm adapted to engage with the handle of an electric iron, and a clamp device in connection with 85 the supporting arm adapted to engage with the handle support.

7. A device of the character described, comprising a supporting arm, a clamp in connection with the supporting arm for engaging the handle structure of an electric iron, an extension in connection with said arm for engaging the handle connecting device, and means in connection with said arm for engaging an electric wire cord. 90 95

8. A device of the character described, comprising a supporting arm, resilient projections integral with said arm adapted to clamp upon the handle structure of an electric iron, means in connection with said arm 100 for coöperating with a part of the handle structure of the iron to support the arm, and means in connection with said arm for engaging an electric wire cord.

9. A device of the character described, 105 comprising a supporting arm, a socket integral with said arm adapted to receive a part of the handle of the iron, and an extension of said arm arranged to coöperate with a part of the handle and iron structure to 110 support the arm, and coöperate with said socket to sustain the arm in an upright position.

10. A device of the character described, comprising a supporting arm, a socket integral with said arm adapted to receive a part of the handle of the iron, a clamp in connection with said arm for engaging the handle structure of the iron, and an extension of said arm arranged to coöperate with 115 a part of the handle and iron structure to support the arm, and coöperate with said socket and said clamp to sustain the arm in an upright position, and means in connection with the upper extremity of said arm for 120 engaging an electric wire cord. 125

11. A device of the character described, comprising a supporting arm, a socket integral with said arm adapted to receive a part of the handle of the iron, a clamp in 130

connection with the arm for engaging the handle structure of the iron, and an extension of said arm arranged to coöperate with a part of the handle and iron structure to support the arm, and coöperate with said socket and said clamp to sustain the arm in an upright position, means intermediate of the upper extremity of the arm and said socket for engaging with an electric wire cord, and means at the upper extremity of 10 the arm for engaging the electric wire cord.

GEORGE BULLOCK.
ARTHUR E. TEMPLEMAN.
